Specification for Design.

Patented June 7, 1921.

Application filed December 28, 1920. Serial No. 433,657. Term of patent 14 years.

To all whom it may concern:

Be it known that we, ALFRED A. GLIDDEN and GLYNN G. BUELL, residents of Watertown, and ELUE O. FRITCH, resident of Belmont, in the county of Middlesex and State of Massachusetts, citizens of the United States, have invented a new, original, and ornamental Design for Tire-Treads, of which the following is a specification, reference being had to the accompanying drawing, forming a part thereof.

Figure 1 is a plan view of a portion of a tire tread, showing our new design.

Fig. 2 is a side elevation of the same.

Fig. 3 is a transverse sectional view.

We claim:

The ornamental design for a tire tread, as shown.
